FIG. III.

UNITED STATES PATENT OFFICE.

WILLIAM B. OLIVER, OF COLLINGSWOOD, NEW JERSEY, ASSIGNOR TO OLIVER ELECTRIC COMPANY, OF PHILADELPHIA, PENNSYLVANIA, A CORPORATION OF PENNSYLVANIA.

ELECTROTHERAPEUTIC APPLIANCE.

1,049,759.

Specification of Letters Patent.

Patented Jan. 7, 1913.

Application filed July 8, 1908. Serial No. 442,457.

To all whom it may concern:

Be it known that I, WILLIAM B. OLIVER, of Collingswood, in the county of Camden and State of New Jersey, have invented certain new and useful Improvements in Electrotherapeutic Appliances, whereof the following is a specification, reference being had to the accompanying drawings.

The object of my invention is to provide an apparatus for treating selected portions of the human body by the employment of mechanical massage in connection with an electric current which may be restricted to the parts undergoing the massage treatment or may be extended so as to include other portions of the body of the patient.

The organization in which my improvements are embodied comprises a handle and a plurality of rollers arranged at suitable distances for convenient passage over the curved as well as the flatter portions of the human frame, the apparatus comprising a self-contained source of electricity as well as an induction coil.

Certain specific features of the invention relate to devices whereby a difference in the character of the circuits and in the locality of their application may be obtained by means of suitable adjustments, so that the electrical treatment may be greatly varied to suit the demands of individual cases.

The arrangement of the rollers and handle is such that powerful penetrative massage strokes may be applied to the tissues of the patient, and the arrangement of the electric circuits is such that not only the immediate region which is undergoing massage, but other portions also of the body and limbs of the patient may be simultaneously subjected to the action of electric currents. Moreover, the currents flowing through the several circuits are inherently of different character and they may be separately or cumulatively employed. The strength of the currents may also be varied or regulated in the usual manner characteristic of electrotherapeutic apparatus.

Furthermore, I provide means whereby in the event of the exhaustion of the self-contained source of electricity, electrical connections may readily be made with an external source of supply, so as to avoid the interruption which might otherwise be due

to the absence of the special cells required for the instrument itself.

I believe that by the use of the improvements about to be described a range and flexibility of application is secured which has never before been possible in electrotherapeutic treatment.

In the accompanying drawings, Figure I, is a side elevation of the device. Fig. II, is a vertical section taken longitudinally of the handle and transversely of the rolls. Fig. III, is a view showing the right hand end of the handle in elevation, and a longitudinal vertical section through the corresponding roll. Fig. IV, is an end elevation as viewed from the left hand side of Fig. I. Fig. V, is a vertical section through the handle taken on the line V, V, in Figs. I, and II. Fig. VI, is a diagrammatic view of the connections by which the various circuits may be made.

In said drawings, the tubular handle 1, is made of hard fiber or other suitable material, and to this handle are attached four depending arms 2, 3, 4, and 5, which are also attached to braces 8, and 9, and form supports for the journal pins of the rolls 10, and 11. Said arms are insulated from each other and from the handle, and are utilized in affording connection with the battery cells, as will be more fully explained.

The construction of both rolls with their electric cells being identical, the description of one will suffice for both. The roll 10, comprises a tubular metallic shell 12, having a peripheral depression 14, formed therein for the reception of a brush contact member 15, which is adapted to bear against the bottom of said depression. In the respective ends of said shell 12, are insulating cups 16, and 17, provided with bushings 18, and 19, respectively, made of insulating material and forming bearings for the journal pins 20, and 21. These pins may be partly threaded and provided with lock nuts 22, 23, whereby they may be secured in adjusted position with their inner ends firmly pressed against the electrodes of the cell.

The cell 25, is preferably of one of the well known types employed in "dry" batteries, and in the instance shown comprises an outer cylindrical metallic container 26, constituting one of the electrodes, and an inner

axial rod 27, which constitutes the other electrode. Said cell is filled with any suitable electrolyte 28, and sealed with a plug 29, of insulating material.

5 Within the tubular handle 1, is a wooden spool 30, on which are wound a primary coil 31, and a secondary coil 32, of standard medical battery type, having a central laminated or filamentous iron core 33, inserted 10 axially in said spool. One end of the primary coil 31, is connected to a contact plate 34, secured to the adjacent end of the handle 1, and the other end of said primary coil is connected to a contact plate 35, secured to 15 the other end of said handle. One end of the secondary coil 32, is connected to a contact plate 36, which is located beside, but insulated from the contact plate 34, and the other end of said secondary coil is connected 20 to the contact plate 35.

Slidably mounted upon the spool 30, so as to move over the primary and secondary coils, is a copper sleeve 37, to which is attached a pointer 38, adapted to pass over a 25 scale 39, on a split metallic tube 40, extending over a portion of the outside of the handle and is intended to be grasped by the hand when the device is operated. By moving the sleeve 37, longitudinally, the induced 30 current may be gradually increased or decreased, as desired, the adjustments being indicated by the pointer 38. At one end of the tube 40, is a tongue 41, which is integral with the metal thereof and is bent radially 35 inward to form a support for the pivoted switch arm 42. Attached to the end of the handle 1, in close proximity to the core 33, and connected to the arm 4, is the vibrating spring 45, of a current interrupter, having 40 an armature 46, secured thereto, and also a small weight 47, to emphasize the action of the spring. A contact screw 50, is mounted in an angular extension of the plate 35, and is adjustable with relation to the vibrating 45 spring 45.

The shell 13, of the roller 11, is in contact with a brush 51, mounted upon the brace 9, and connected to the contact plate 35. A switch arm 52, is pivotally mounted upon a 50 horizontal extension 53, of a contact plate 54, secured to the end of the handle 1, above the vibrating spring 45. Said switch arm 52, is bent to come in contact with the curved upper portions of the arms 4, and 5, 55 as desired. A switch arm 60, is pivotally mounted upon an upwardly projecting extension 61, of an angle plate 62, passing between the brace 8, and the under side of the tubular handle 1. Said angle plate is provided with a depending projection 63, to 60 which the brush 15, is connected. The contact plates 34, 35, and 36, are provided with threaded holes 64, 65, and 66, respectively, with which electrodes or applicators of any 65 desired type commonly used with medical

batteries may be employed. In the diagrammatic view of Fig. VI, I have conventionally indicated handles 70, and 71, provided with sponges at their ends and connected by wires 73, and 74, respectively, (see 70 dotted lines) with the plates 34, and 36.

In order to provide means for connecting an auxiliary source of current with the device in case of the exhaustion of the cells, and to obviate any delay in getting a new 75 supply of the special cells, I provide the auxiliary contact sockets 80, and 81, which are mounted in the brace 8, and to which any common form of battery 82, may be connected through the conductors 83, and 84, 80 (as indicated by the conventional representations and dotted lines in Fig. VI).

The socket 80, is connected to the arm 2, by means of a wire 85, and said socket is also connected to the contact plate 54, by 85 means of a wire 86, passing through the handle 1. The socket 81, is connected to the contact plate 34, by a wire 87, and to the arm 3, by a wire 88.

The arm 4, is connected to the inner electrode 90, of the cell in the roller 11, by means of a journal pin 91, and the arm 5, is connected to the outer electrode 92, by means of the journal pin 93.

With the connections arranged as shown 95 in Fig. VI, and the switch arm 52, in contact with the arm 4, the following circuits may be produced: The primary or exciting current from the cell 25 passes from electrode 27, through pin 21, arm 2, wire 85, socket 100 80, wire 86, plate 54, switch arm 52, contact 4, vibrator 45, contact screw 50, plate 35, primary coil 31, plate 34, wire 87, socket 81, wire 88, arm 3, pin 20, to outer electrode 26, of the cell 25. The current induced in 105 the secondary coil 32, flows through plate 35, brush 51, shell 13, localized through that portion of the patient extending between the rolls and indicated by the dot and dash lines 95, and 97; shell 12, brush 15, switch arm 60, 110 to plate 36, to the other terminal of the secondary coil. This gives a localized application of the Faradic or induced secondary current. Another current moreover is re-induced in the primary coil 31, in accordance 115 with the alternations and variations of the induced current flowing through the secondary coil, such re-induced current, (which for purposes of convenient description may be referred to as the tertiary current), is 120 entirely distinct from the primary or exciting current from the battery itself, but flows in a direction similar thereto, and is of lower potential than the secondary current. Said tertiary re-induced current in the primary 125 coil 31, flows from one terminal thereof through the plate 35, and brush 51, to shell 13, passes thence through that portion of the body which is in contact with the shell 13, to the arm and hand of the patient (as 130

indicated by dotted and dash lines 95 and 96), thence to the sleeve 40, which is grasped by the hand of the patient, and thence through the tongue 41, switch arm 5 42, and plate 34, to the other terminal of the primary coil 31.

With the connections and switches as shown in Fig. VI, the secondary and tertiary currents will divide, a portion of both currents

10 passing through their regular paths as above described, while the other portions of these currents will pass through a third circuit with cumulative effect. The path of this third circuit is as follows: from secondary coil #32 to plate 35, primary coil 31, to plate 34, to switch arm 42, tongue 41, thence to sleeve 40, which is grasped by the hand of the patient, thence through the arm and body (as indicated by dotted and dashed lines 96 and 97) to shell 12, and brush 15, switch arm 60, and plate 36, back to the other terminal of the secondary coil 32.

If the switch arm 60, be disconnected from the plates 34, and 36, and the arm 42, connected with the plate 34, there will be an application of the tertiary current re-induced in the primary coil through the hand, arm, and body. If the switch arm 42, be swung over to the plate 36, there will be a similar diffused application of the secondary current, and if the switch arm 42, be disconnected from both the plates 34, and 36, and the arm 60, be connected to plate 34, there will be an application of the tertiary current, re-induced in the primary coil, which will be localized in that portion of the body which is between the rollers 10, and 11. If the switch arm 60, be swung over to the plate 36, there will be a similar localized application of the secondary current. If the hand electrodes 70, and 71, be grasped and connected to plates 34, and 36, respectively, with the other connections as shown in Fig. VI, there will be an application of the tertiary current re-induced in the primary coil, and the secondary current induced in the secondary coil, cumulatively combined. If the hand electrode 71, be connected to socket 65, there will be an application of tertiary current re-induced in the primary circuit alone. If the electrodes be connected to sockets 65, and 66, there will be an application of the secondary current alone.

55 When it is desired to increase the strength of the primary and secondary currents, this may be effected by turning the switch arm 52, to connect with contact 5, thereby placing the two cells in series.

60 In addition to the novel and valuable features above described as characteristic of the electrical possibilities of the device, it will be noted that structurally the apparatus is of great simplicity and strength and that the 65 parts are readily accessible for adjustment

and can be removed and replaced with great facility.

Having thus described my invention, I claim:

1. An electrical massage apparatus comprising the following parts in combination: a handle adapted to act as an electrode; a massage roller having a conducting surface; a source of electricity insulated from said surface; an induction coil; and an automatic current interrupting device; said induction coil and current interrupting device being self-contained; and devices whereby said handle and the surface of said roller may be placed in circuit with the secondary element of said induction coil; whereby the circuit for the induced current may be completed through the person of the patient from points respectively in contact with the handle and the surface of the roller. 70

2. An electrical massage apparatus comprising the following parts in combination: a handle adapted to act as an electrode; a plurality of massage rollers, having conducting surfaces; a source of electricity insulated from said surfaces; an induction coil; and an automatic current interrupting device; an intensity regulator; and devices whereby the surface of one or both of said rollers and said handle may be placed in 80 circuit with the secondary coil, whereby the circuit of the secondary current may be completed through the person of the patient from points in contact with said handle and said roller or rollers respectively, 90 and said current may be varied in strength. 100

3. An electrical massage apparatus comprising the following parts in combination: a handle electrode; a plurality of massage electrodes; an induction coil; a source of 105 electricity for the primary circuit of said coil; a current interrupting device; and means for electrically connecting the said massage electrodes, jointly or severally, and the said handle electrode, in circuit with the 110 resultant currents of the primary and secondary coils of said induction device.

4. In an electrical massage apparatus, the combination of a handle; a plurality of massage rollers; a self-contained battery 115 cell; an induction coil; two of said rollers and said handle being arranged to operate as electrodes of opposite polarity and insulated from the direct path of the primary circuit; and means for connecting said electrodes in circuit, with either of the induced or resultant currents of the primary and secondary coils.

5. In an electrical massage apparatus, the combination of a hollow handle; an induction coil contained therein; a current interrupting device; a plurality of massage rollers each of said rollers comprising an external metallic shell adapted to act as an electrode and an internal battery cell in- 125 130

- sulated from said shells; electrical connec-
tions for said battery arranged in axial re-
lation to said roller, but insulated from the
peripheral surface thereof, said electrical
connections leading to the primary coil;
and contact brushes bearing upon the ex-
ternal periphery of said rollers, and in cir-
cuit with the induced, or resultant, currents
of the said induction coil.
- 10 6. In an electrical massage apparatus, the
combination of a hollow handle; an induc-
tion coil contained therein; a current inter-
rupting device; a plurality of massage rollers,
each of said rollers comprising an ex-
15 ternal metallic shell adapted to act as an
electrode and an internal battery cell in-
sulated from said shell; electrical connec-
tions for said battery arranged in axial re-
lation to said roller, but insulated from the
20 peripheral surface thereof, said electrical
connections leading from the primary coil;
contact brushes bearing upon the external
periphery of said rollers and being pro-
vided with electrical connections in circuit
25 with the induced, or resultant currents of
said induction coil; a movable metallic
sleeve longitudinally adjustable with re-
lation to the induction coil; and a metal tube
inclosing a portion of the handle and elec-
30 trically connected with one of the electric
circuits.
7. In an electrical massage apparatus, the
combination of a handle; a plurality of
massage rollers; a primary and secondary
35 induction coil; said rollers and said handle
being arranged to operate as electrodes of
opposite polarity; and switch means where-
by the handle and a roller may be included
in one circuit and the rollers in the other
40 circuit of the resultant, or induced, currents
of the respective coils.
8. In an electrical massage apparatus, the
combination of a hollow handle; an induc-
tion coil contained within said handle; hol-
45 low massage rollers; battery cells contained
within said rollers, said battery cells being

electrically insulated from the external sur-
face of the rollers, but electrically connected
with the primary induction coil; and means
whereby the external surfaces of the rollers 50
may be electrically connected with the re-
sultant, or induced currents of the primary
and secondary coils.

9. In an electrical massage apparatus, the
combination of a hollow handle; an induc- 55
tion coil contained within said handle; hol-
low massage rollers; battery cells contained
within said rollers, said battery cells being
electrically insulated from the external sur-
face of the roller, but electrically connected 60
with the primary induction coil; means
whereby the external surfaces of the rollers
may be electrically connected in circuit with
the resultant, or induced currents of the in-
duction coil; and switching devices whereby 65
one or more of the battery cells may be
placed in circuit with the primary coil.

10. In an electro-therapeutic apparatus
comprising an induction coil device, and
means for inducing secondary and tertiary 70
or resultant currents in the respective coils
thereof; the combination of an electrode
common to the circuit of both coils; and a
plurality of individual electrodes severally
in circuit with the respective coils; whereby, 75
on application to the patient, the circuit for
one of said currents may be completed
through the common electrode and one of
the individual electrodes, the circuit for an-
other of said currents may be completed 80
through the common electrode and another
of the individual electrodes, and the circuits
of both currents cumulatively applied may
be completed through individual electrodes.

In testimony whereof, I have hereunto 85
signed my name, at Philadelphia, Pennsyl-
vania, this sixth day of July 1908.

WILLIAM B. OLIVER.
